(57) **CLAIM**

The ornamental design for a shaping belt, as shown and described.

DESCRIPTION

FIG. 1 is a front perspective view of a shaping belt, showing my new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof; and,

FIG. 9 is a front perspective view of the shaping belt, shown with straps fastened as in condition of use.

The broken lines in the drawings illustrate the portions of the shaping belt, which form no part of the claimed design.
